UNITED STATES PATENT OFFICE.

ROBERT H. BENTLEY, OF HARTFORD, CONNECTICUT, ASSIGNOR TO THE HART & HEGERMAN MANUFACTURING COMPANY, OF HARTFORD, CONNECTICUT, A CORPORATION OF CONNECTICUT.

ELECTRIC SNAP SWITCH..

Application filed February 7, 1921. Serial No. 442,922.

To all whom it may concern:

Be it known that ROBERT H. BENTLEY, a citizen of the United States, residing at Hartford, in the county of Hartford and State of Connecticut, has invented certain new and useful Improvements in Electric Snap Switches, of which the following is a specification.

This invention relates to electric snap switches. While it is conceivable that the improvements can be embodied in switches of various types the same are of particular utility when incorporated in an article of the character set forth having a movable and desirably oscillatory or swinging switching member, one of the primary objects of the invention being the provision of means of an effective character by which necessary starting torque can be given to the switching mechanism. In the construction shown, the switching member involves a main portion and an auxiliary portion carried thereby. When this construction is present another object I have in view is to have the main or mounting portion of the switching member yieldable, and the head or supplemental portion stiff or relatively so, to thus adapt the switching member to coact with rigid contacts which are engaged by the main or mounting portion when the switch is in the "on" relation.

In the drawings accompanying and forming part of the present specification I have shown in detail a form, one of several, of the invention which to enable those skilled in the art to practice the same will be set forth fully in the following description. Obviously I am not restricted to the disclosure made by said drawings and description. I may depart therefrom in several respects within the scope of the invention defined by the claims following said description.

Referring to said drawings:

Figure 1 is a top plan view of a switch involving the invention.

Fig. 2 is a sectional side elevation of the same, the sectional plane cutting the body of the switch and the switching member.

Fig. 3 is a detail in cross section of a portion of the base, the switching member and the actuator.

Fig. 4 is a diagrammatic detail. Like characters refer to like parts throughout the several views.

The operative parts of the switch are supported by a suitable base such as that denoted by 2 and which generally consists of some insulating composition such as common in switches of this type. The base usually supports a casing which houses the switching mechanism and contacts, but which I have for clearness omitted. The operation of the switching mechanism is initiated by an actuator such as that denoted in a general way by 3. This actuator as shown comprises a body as 4 for instance a strip or yoke-like piece of metal onto the ends of which are mounted the composition buttons 5. The base also has contacts 6 fastened to the base and to which the wires 7 are connected. As shown the contacts or terminals 6 are stationary and inelastic or rigid and the free end portion of the switching member, hereinafter described, is projected between these contacts when the switching member is in the "on" relation. The active portions of the contacts have forwardly diverging faces 8 along which the free end of the switching member rides in its passage toward the parallel active faces 9 of the contacts as shown in Fig. 1. The switching member is denoted in a general way by 10 and as shown comprises a body or main member 11 and a supplemental member 12 movably supported on the body 11. The body or main member 11 as shown is pivotally supported at 13 for swinging movement by the base 2, the pivot 13 being situated below the body 4 of the actuator. This body or main member 11 is of yoke or practically U form and straddles the body 4 of the actuator, the transverse portion of the yoke being obviously below the body 4 and the branches thereof being at opposite sides of said body 4. The supplemental member constitutes a head or crown piece therefor and it is practically in the form of a yoke or inverted U-shaped part flexibly or pivotally connected with the main or body member 11. As shown the side branches of the supplemental member 12 have lateral offsets or

studs 14 which bottom in the notches or slots 15 of the side branches of the body or main member 11 from which it will be clear that the supplemental member 12 can move 5 relatively to the body or main member 11 which is an important consideration. As shown the transverse or cross portion of the supplemental switching member 12 is furnished with a depending projection or 10 tongue 16 which has a slidable connection with the shank of the swinging or rocking body 17, the foot 18 of which is forked to straddle the cross piece 19 of the body 4 of the actuator. The shank of the rocking or 15 swinging part 17 is surrounded as shown by a coiled spring 20 the lower end of which engages the foot 18 and the upper end of which engages the transverse portion of the supplemental part 12 of the switching member, the spring being coiled about the shank 20 of the part 17 and also about the projection or tongue 16.

It is proper to note that the main or mounting portion 11 of the switching member in the construction shown, is desirably 25 of yieldable nature while the supplemental member 12 is not. These two members are of yoke form and the branches of the yoke of the main or mounting portion enter between the fixed contacts 6, and on the entering motion slightly approach each other so 30 as to insure a solid firm contact.

In Fig. 2 the dotted lines show the switching member 10 as being in the "off" relation. 35 It will be assumed that it is desired to obtain the closed circuited relation. In this event the following procedure will be adopted. The actuator 3 will be thrust toward the left in Fig. 2 from the dotted line position. I might explain that on the movement of the actuator 3, the supplemental switching portion 12 through the agency of the interposed spring 20 is swung toward the dead center line, the spring at the same time 40 being conditioned to impart a snap movement, which is effected the instant that the supplemental switching portion 12 crosses the dead center line. At this point the conditioned spring by reaction, will snap the 45 primary switching portion 12 so that in the event the circuit is open at the institution of the action described, the sides of the main switching portion will be caused to be snapped substantially between the parallel 50 faces of the contacts 6. The opposite action 55 of the switching member from the full line to the dotted line position is practically the reverse of that described.

It will be clear that owing to the nature 60 of the switching member I can when it is at the limit of either of its movements give it a starting torque sufficient to insure the stroke thereof, this whether the switching member be oscillatory or not.

65 In the diagram, Fig. 4, I have illustrated

the action of the moving parts in travelling from one extreme to the other. This is supposed to be the motion in travelling from "off" to "on." The opposite action or from "off" to "on" would be the reverse of that 70 illustrated. In this view *a* and *a'* are assumed to be the extreme positions of a connection between the rocking body or spring carrier 17 and the actuator 5, while *b* represents the pivot between the main switching member 11 and the supporting body 2. The line *b*—*c* represents the longitudinal central line of the main portion 11 of the switching member when in one of its extreme positions. The point *d* represents the pivotal 80 connection between the main switching portion 11 and the supplemental switching portion 12. The line *d*—*e* represents the central line of the supplemental switching portion 12 when the connection 19 between the rocking body 17 and the actuator 15 is at the point *a'*. It will therefore be clear that the spring 20 when the parts are in this particular position, exerts its thrust in a line 85 between points *a'* and *e* and thus exerts a greater starting torque on the main switching portion 11 than it would if the thrust of the spring were exerted between the points *a'* and *c* as would be the case were the supplemental switching portion 12 or its equivalent not present.

What I claim is:

1. An electric switch comprising a switching member having a main swinging portion and an auxiliary portion mounted for swinging movement on the main portion, an actuator for the switching member mounted for back and forth movement in a straight line, a body having a flexible connection both with the actuator and the auxiliary portion of the switch, and a spring around the body and acting against the auxiliary portion of the switch, the actuator on its movement acting to condition the spring to snap the switching member. 100

2. An electric switch comprising a switching member having main and auxiliary portions each in the form of a yoke, the yokes being interfitted, the main portion being mounted for swinging movement and the auxiliary portion swinging on the main portion, an actuator for the switching member mounted for back and forth motion and disposed between the sides of the main portion of the switching member, a body connected flexibly with the actuator and connected operatively with the auxiliary portion of the switching member, and a spring around the body to act directly against said switching portion, the actuator on its motion conditioning the spring to impart a snap movement to the switching member. 115

3. An electric switch comprising a movably mounted switching member, an actuator for the switching member, spring means 120

between the switching member and the actuator, the actuator being movable to condition the spring means to impart a snap movement to the switching member, the latter comprising main and auxiliary portions movably connected with each other, the auxiliary portion being stiff, and contacts between which the main portion is projectable, said main portion being yieldable to enter between the contacts. 10

In testimony whereof I affix my signature.

ROBERT H. BENTLEY.
